UNITED STATES PATENT OFFICE.

NATHAN LESTER, OF WORCESTER, MASSACHUSETTS.

DIE-CASTING MACHINE.

REISSUED

Application filed December 22, 1926. Serial No. 156,477.

This invention relates to a machine for casting metals in metal molds, known as dies.

The principal objects of the invention are 5 to provide a separable die of the ordinary type with means for opening and closing it, preferably under oil pressure, and with means whereby when the die is opened the casting will be ejected by the die operating 10 means; to provide controlling mechanism by which the proper sequence of operations is caused to take place without any attention on the part of the operator except to turn a lever for opening and closing the dies and 15 another lever for operating the pump; to construct the mechanism for performing the two operations in such a way that the operator cannot turn either handle at the wrong time and that the metal cannot be 20 forced out of the pump unless the mold is closed and forced up to casting position; to provide means operated by the die operating mechanism for moving the pump in the melting pot or ladle up to the position for 25 casting and making sure that the same is in that position before the metal is forced into the mold; to provide a casting pump in which the nozzle will move with the pump accurately to enter the sprue in such a way 30 as to prevent the formation of a projection on the cast metal that would prevent or interfere with the removal of the casting; to provide a movable pump normally submerged in the metal in the casting pot when 35 not in casting position for the purpose of keeping it heated and filling it with metal; to provide an air operated pump with a metal ejecting nozzle and an air receiving nozzle, so related that they will both come 40 simultaneously into proper position to connect the pump with its air supply and the dies; to provide means for cooling the stationary gland of the mold, which really constitutes the sprue, in order to prolong the 45 life of this important element, and to provide improvements in the mechanisms and various features of construction in carrying out these objects.

Reference is to be had to the accompanying drawings in which

Fig. 1 is a side view of a complete die casting machine constructed in accordance with this invention;

Fig. 2 is a plan of means for controlling 55 the admission of power fluid to the cylinder

which operates the dies and air to the pump;

Fig. 3 is a side view of the connecting parts between the die operating means and pump;

Fig. 4 is an end view of the same;

Fig. 5 is a sectional view on the line 5—5 of Fig. 3;

Figs. 6 and 7 are enlarged views of the die operating mechanism shown in two extreme positions;

Figs. 8 and 9 are sectional views on the lines 8—8 and 9—9 respectively of Fig. 7;

Fig. 10 is an enlarged side view of the pump and its actuating mechanism;

Fig. 11 is a front elevation on enlarged 70 scale of the front mold wall showing the air connections at this point and the water cooling means for the sprue or gland;

Fig. 12 is a central longitudinal sectional view of the pump approaching casting position;

Fig. 13 is an end view of the same;

Fig. 14 is a sectional view of the cooling device above mentioned; and

Figs. 15, 16 and 17 are views of the cams 80 which control the operation of the pump and dies, shown in three different positions.

Referring first to the first three sheets of drawings, which illustrate particularly the die operating mechanism, it will be seen that the machine embodies a frame 10 carrying a stationary vertical plate 11 against which one of the dies 12 is adapted to bear and a slidable vertical plate 13 carrying the other die 14 with it. There is also a stationary end piece 15 which is mounted on ways on the bed or frame 10 and is adjustable therewith by bolts extending into or through the frame. The adjustment is to provide for dies of different thickness. 95 This end plate 15 is secured to the end plate 11 by threaded horizontal rods 16. The plate 13 has a slide or base 19 extending to the rear adapted to slide on the ways 18 at the top of this part of the frame 10.

Supported by the end plate 15 is a cylinder 20 within which is a piston 21 provided with a piston rod 22 which carries a sliding rack 23 which is of a double character as it has rack teeth on its opposite sides. This rack 105 is adjusted on the rod by means of screw and nut connection 24 and it is provided with a downwardly extending portion having longitudinal guide surfaces 25 guided in a pair of gibbs 26 secured to the slide or base 110

19 so that the rack will be constrained to move in a rectilinear manner on the top of this part of the frame.

The vertical plate 15, which is fixed in stationary position, carries brackets 27 carrying studs 28 on opposite sides of the rack. On each of the pivot studs is pivoted a gear segment 29 meshing with one of the racks. Fixed to each segment is an arm 30 which 10 swings with the gear segment and is connected by a lever 38 with a link 39 pivoted thereto and also pivoted on a projection on the movable plate 13. These levers 38 and arms 39 are provided with projections 15 40 and 41 which, when the parts are in the extreme position shown in Fig. 7, abut against each other and prevent the link and lever constructions from passing beyond the dead center, thus limiting the action. The 20 levers 38 are pivoted, it will be obvious, at one end to the arms 30 and to the link 39 at the opposite end. In the middle they are pivoted to a head 42 which is arranged to move longitudinally but at a different 25 rate of speed from the rack 23. This will be obvious from the connections shown in Figs. 6 and 7. This head is provided with a pair of ejectors 43 in the form of rods or plates. While in casting position, these 30 ejectors project beyond the plate 13 into spaces in the die 14 and extend clear to the casting face of the mold cavity of which their ends constitute a part. When moved from the position shown in Fig. 7, to that 35 shown in Fig. 8, these rods eject a casting. This ejection is due to the fact that, on account of the leverage, the die 14 is retracted faster than the head 42 and ejectors 43.

The cylinder and plunger 21 which are 40 used for operating the die section 14 and the ejection of the casting is intended to be operated by any kind of fluid but I have shown herein a mechanism for operating it by oil. The oil is furnished by an oil pump 45 43^a, the details of which are not shown, but it delivers and discharges through two pipes 44 and 45 to a valve casing 46 and is so constructed that the oil in these pipes is under pressure all the time while the oil pump is 50 running. In this casing 46 there are valves, mounted on a shaft 50, which control the passage of oil from the pipes 44 and 45 respectively to two pipes 47 and 48 which lead into the opposite ends of the cylinder 20. It will be obvious that in accordance with 55 the operation of these valves the oil will be admitted to one end or the other of the cylinder and force the piston back or forward. This cylinder itself has no valves, being controlled entirely by the direction of flow of 60 the operating liquid. The valves in the casing 46 are located on the shaft 50 which is provided with an operating handle 51 so that the operation of this part of the 65 machine is controlled by the shifting of this

handle back and forth. The valves operated by this handle are so related to each other, of course, that the motor fluid cannot be forced into both ends of the cylinder 20 at the same time. The oil pump and these 70 valves are not shown as they are obtainable on the market and the details thereof are not a part of this invention.

Mounted on the base or slide 19 is a rack 52 which can be adjusted along the slide 75 19. Mounted on brackets 53 on the frame 10 is a shaft 54 carrying a gear 55 meshing with the rack 52. On this shaft 54 is a crank 56 which is connected with a rod 57. The reciprocation of the rack 52 causes the 80 gear to oscillate and the rod 57 to be moved back and forth. This rod is provided with an adjusting screw 58 meshing with a rack 59 cut on the surface of a link 60 which is in turn connected with an arm 61 for a purpose to be described. It will be seen therefore that the reciprocation of the double 85 rack 23 by means of the piston in the cylinder opens and closes the die and ejects the casting therefrom and further operates this 90 arm 61 to swing it about its axis. This arm 61 operates the pump to fill the dies as will appear below.

The pumping means for this machine comprises a melting furnace 62, preferably on 95 the frame 10, having therein a melting pot 63 in which a supply of metal is maintained. The pump is operated by air pressure controlled from a handle or lever 64 fixed on a shaft 68 which handle is located near the 100 handle 51 so that the operator can attend to both of them. The shaft 68 extends to the pump and is provided with two cams or eccentricities 73 and 74 which operate valves in a 105 valve casing 77 to control the connection of the pump with two pipes 75 and 76 which, as will be described later, exert pressure on the metal in the pump to force it into the mold at certain times.

On the controlling shaft 50 is a cam 66. 110 This cam is of circular shape all around except for a notch 67 at one point. On the shaft 68 below there is another cam 69 which is of general circular form but also with a notch 70 of the same size and shape as the 115 notch 67. Each of these notches, as will be observed from comparison of Figs. 15, 16 and 17, is of such shape that the other cam can rotate when in registration with that notch but not otherwise. Each notch is of 120 the shape of an arc of the circle of the other cam. The shafts 50 and 68 have their axes at a distance apart less, by the width of one of the notches, than the sum of the radii of the two cams.

In the position shown in Fig. 16, either cam can be turned from its position, but in the positions shown in Figs. 15 and 17 only one cam can turn. The cam 69 also has another notch 71 which cooperates with a pin 125 130

72 to constitute a stop. This cam simply oscillates the length of this slot and cannot move beyond it. The valves 73 and 74 connect the air inlet 75 with the pipe 76 when the cam 74 closes its valve and the cam 73 opens the other valve.

The control of the air to the pump and the control of the oil to the operating cylinder are both manual. The latter, as stated above, 10 actuates the arm 61 which is located on a shaft 91. This shaft is mounted on a base 83 which is provided with ways below and is capable of a slight sliding motion. This is an important feature, because it is secured 15 by longitudinal rod 84 to the stationary plate 11. On account of the expansion of the metal of which the parts are made under the influence of heat and the subsequent contraction, some of the metal parts would 20 break. The support 83 is mounted in this way so that it can move back and forth, but of course it will be understood that this is only a slight movement in accordance with the temperature of the parts on which these 25 elements are supported.

On the shaft 91 is an arm 85. This is connected by link 88 with a stud 86 on the pump 81. This pump is of the goose-neck type provided with a nozzle 82 and located within 30 the melting pot and normally below the level of metal therein so that it will fill by gravity through the nozzle. It is supported by a pair of brackets 87 extending upwardly from the melting furnace and carrying a cross shaft 89. On this cross shaft is pivoted a 35 link 90 which depends therefrom and is connected with the stud 86 so as to support one end of the melting pot from above. Each bracket 87 carries at the top a clamp 93 having projecting ends below extending under 40 the ends of the bearing and held in position by a bolt 94.

At the top of the pot 81 are integral lugs 103, under which extends the ends of a clamp 45 104 similar to the clamp 93 secured above by a bolt 105 for holding the cover 106 on the pot. This cover is provided with an air passage 107 and a nozzle 108. This nozzle is adapted to fit in a cup-shaped nipple 109 50 which is directly connected with the pipe 76. Adjacent to this nipple 109 are guide pins 110 entering holes in the cover 106 to guide the pump to move rectilinearly when it gets 55 up to position for operation. When this happens the nozzle 82 is also registered in a gland 111 which is provided with a water circulating groove 112 applied in any desired way to keep this gland cool and extend its life. On the furnace is a stud 96 mounted in 60 suitable bearings and carrying a plate 97 which can be adjusted by screws 98 to have the proper angle so that link 99 pivoted on this plate 97 will be located in the proper position. This link is provided with a transverse pin 100 which receives a downwardly

opening rest or bearing 101 on a projection 102 fixed to, or cast integral with, the pneumatic pump 81. This arrangement of the parts 91, 89 and 100, together with the location of the end of the rod 60 with respect to 70 the plate 13, allows of the proper operation of the pneumatic pump 81 from the filling position shown in Fig. 10 to casting position shown in Fig. 1 and back again.

The operation of the machine is as follows:—With the mold open and the pump in the position shown in Fig. 10, the crank 51 is turned a half revolution from the position in which the handle is vertically above the shaft 50 to its opposite position 75 in which it is vertically below it as shown. The valves are in position to prevent flow of air to the pump the dies being open and being held open by the oil in the pipe 47. Now the first effect of the turning of the 80 handle into this position is to open one valve in the casing 46 to release the oil from in front of the piston 21. Then the other valve is opened to allow the oil to be forced through the pipe 48 into the cylinder 85 behind the piston. The result of this is to move the parts from the position shown in Fig. 6 to the position shown in Fig. 7. This forces forward the sliding plate 13, closes the dies, and withdraws the ejectors 43. The 85 movement of the rack 52 forward actuates the rod 60 to swing the pump 81 upwardly. As it reaches the upward limit of its stroke, it also moves forwardly through the straightening out of the construction formed of the arm 85 and the link 88 and forces the nozzle 82 directly into the sprue opening in the plate 11. At the same time the crank 51, having now reached the bottom, the notch 67 will have come into register 90 with the notch 70 from the position shown in Fig. 15 into that shown in Fig. 16. Now the handle 64 on the shaft 68 is turned to bring this shaft around. This admits air to the pneumatic pump 81 at the top as will 95 be obvious. Now the metal is forced into the mold by the air. The parts are left in this condition a very short period, just long enough for the casting to chill and retain its shape. Then the handle 64 is turned back 100 and the air released from the top of the metal in the pump and then exhausted. This having been accomplished, the crank 51 is turned the rest of the way around the 105 circle to its original position. This results in the opposite action of the valves in the casing 46 so as to release the oil from the outer side of the piston in the cylinder 20. Immediately the other valve changes and the oil is forced through the pipe 47 to 110 force back the piston. This restores the parts to the position shown in Fig. 6 and it will be seen that the ejectors 43, although drawn back slightly, are not drawn back 115 as much as the plate 13. Therefore the cast- 120

125

ing in the mold is ejected by this action although the die 14 is attached to the plate 13 and drawn back with it.

It will be seen therefore that the dies are manipulated to open and close simply by the turning of the handle 51 around 180 degrees and that the control of the air to the pump is also accomplished in a very simple way and controlled absolutely by the position of the handle 51 but operated by the handle 64. The pneumatic pump is moved bodily under the control of the handle 51 and the location of the several points of support and connections which have been shown. It is forced to assume the different positions in proper sequence without any attention on the part of the operator except to operate the handles 51 and 64. The casting is released from the mold on account of the arrangement of the nozzle of the pump and the ejecting devices which have been described in full. This ejection is not left to chance but is made positive by the ejectors which will force it out, even though there might be something to cause it otherwise to stick. The whole operation is very simple and the machine itself is reduced to a small number of parts and yet has all the safety features which are necessary in these machines.

Although I have illustrated and described only a single form of the invention I am aware of the fact that modifications can be made therein by any person skilled in the art without departing from the scope of the invention as expressed in the claims.

Therefore, I do not wish to be limited to all the details of construction herein shown and described, but what I do claim is:—

40 1. In a die casting machine, the combination with a piston and cylinder, of an oil pump, two outlet pipes from the oil pump, a pipe extending to each end of said cylinder for conducting the fluid to operate the piston, a valve casing to which all of said pipes extend, a shaft in said valve casing, means for connecting one pair of pipes with the other pair so that the oil can be supplied to either end of the cylinder for operating the piston and there will be no chance for it to enter both ends at the same time, and a handle on the shaft for oscillating it.

45 2. In a die casting machine, the combination with a pair of dies and means for operating the dies comprising a double rack and gear segments on the opposite sides of the rack, a slide connected with said gear segments for reciprocation to operate one of the dies, and guides on said slide for receiving the rack and guiding it to move in a rectangular manner.

50 3. The combination with a pair of dies and a rod, of means for reciprocating said rod, of a double rack adjustably fixed on the rod, a pair of gear segments on opposite

sides of the rack, meshing therewith, and each pivoted at a stationary point, levers pivotally connected with the segments, a link pivoted to the other end of each lever and to one die, a head freely slideable and having an ejector for ejecting a casting from the mold, said head being pivoted to said levers, whereby when the rod is withdrawn the head will be withdrawn but at a slower rate so that the ejectors will project further and eject the casting.

4. In a die casting machine, the combination with a pair of dies, an ejector for the casting, and means for operating the dies comprising a double rack and gear segments on the opposite sides of the rack, a slide connected with said gear segments for reciprocating one of the dies and ejector, another rack fixed with respect to said slide, a gear meshing with the last-named rack and adapted to turn on a stationary axis and having an arm projecting from its shaft, a pump for supplying the dies with metal, and means operated by said arm for operating the pump.

5. In a die casting machine, the combination with a pair of dies and means for operating one of them, of a rack connected to and movable with one die when it is operated, a gear meshing with said rack, an adjustable link connected with said gear to be reciprocated thereby as the gear oscillates, a pump for supplying the dies with molten metal, and means operated by said link for moving the pump bodily up to casting position.

6. In a pump for a die casting machine, the combination with a melting pot, of a pump body adapted to be submerged in the metal of the melting pot for filling the pump, means for moving said pump bodily, said pump having a horizontal nozzle for delivering to the dies in a horizontal direction a second nozzle above, and a stationary plate having a metal receiving gland for receiving the lower nozzle and a fixed nipple connected with a compressed air supply for receiving the second nozzle so that air can be admitted to the pump over the metal therein, the two nozzles being adapted to come to their two seats simultaneously as the pump moves up to casting position.

7. In a pump for a die casting machine, the combination with a melting pot, of a pump body adapted to be submerged in the metal of the melting pot for filling the pump and heating it, means for reciprocating and rocking said pump with a motion that will dip it in the molten metal and fill it through its nozzle and bring it up out of the metal for delivery, said pump having a nozzle for delivering to the dies, and a second nozzle above, a nipple connected with a compressed air supply for receiving the second nozzle so that air can be admitted to the pump over

the molten metal, the two nozzles being adapted to come to their two seats simultaneously as the pump moves up to casting position, a plate on which one member of a 5 pair of dies is mounted, said plate having an opening for receiving the metal delivery nozzle, and a gland in said opening, the nipple also being supported in fixed position on said plate.

10 8. In a pump for a die casting machine, the combination with a melting pot, of a pump body adapted to be submerged in the metal of the melting pot for filling the pump and heating it, a cover for the pump, 15 means for reciprocating said pump with a motion that will dip it in the molten metal and then fill it and bring it up out of the metal for delivery, said pump having a nozzle for delivering to the dies and a second 20 nozzle above, a nipple connected with a compressed air supply for receiving the second nozzle so that air can be admitted to the pump, the two nozzles being adapted to come to their two seats simultaneously as

the pump moves up to casting position, horizontal guide rods carried by said plate adjacent to said nipple adapted to engage the top of the pump for guiding both nozzles horizontally into proper position, and means 25 for clamping the cover on the pump. 30

9. In a pump for delivering molten metal, the combination with a melting pot, of a pump body located therein, means for moving the pump body from a position in which its nozzle will dip under the metal in the 35 pot to fill the pump upwardly and then horizontally to a position in which it will engage the dies for delivering metal thereto, said means comprising a shaft with arms thereon for moving the pump as the shaft turns, 40 a support for said shaft, and means on the furnace for carrying said support in a manner in which it is free to reciprocate to compensate for contraction and expansion of the parts of the device. 45

In testimony whereof I have hereunto affixed my signature.

NATHAN LESTER.
